UNITED STATES PATENT OFFICE.

WILLARD H. BROWNELL, OF BATTLECREEK, MICHIGAN.

ERASER-TIP FOR LEAD-PENCILS.

SPECIFICATION forming part of Letters Patent No. 737,070, dated August 25, 1903.

Application filed April 21, 1902. Serial No. 103,949. (No model.)

To all whom it may concern:

Be it known that I, WILLARD H. BROWNELL, a citizen of the United States, residing at the city of Battlecreek, in the county of Calhoun and State of Michigan, have invented a certain new and useful Eraser-Tip for Lead-Pencils, of which the following is a specification.

This invention relates to rubber tips for lead-pencils.

The object of the invention is to provide an improved rubber or similar elastic eraser-tip for lead-pencils with a secure retaining means, whereby an elongated piece of erasive material can be made use of and quickly and easily adjusted to compensate for wear or to protect the same, thus making it entirely practical to make use of a superior erasive material, as the same can be transferred from pencil to pencil as the same are used up.

Further objects will definitely appear in the detailed description to follow.

I accomplish the objects of my invention by the devices and means described in the following specification.

The invention is clearly defined, and pointed out in the claims.

A structure embodying the features of my invention is fully illustrated in the accompanying drawings, forming a part of this specification, in which—

Figure 1 is an enlarged view of the structure embodying the features of my invention. Fig. 2 is an enlarged detail view of the same, the pencil and erasive material being shown in full lines.

In the drawings similar letters of reference refer to the similar parts in both views.

Referring to the lettered parts of the drawings, A represents a sleeve slotted at the bottom, as at I, to permit of its being slipped over a suitable lead-pencil, as J. The upper end of the sleeve A is slotted at B. Inwardly-projecting teeth or lugs F are formed in the upper part of the sleeve A by indentations in the sleeve, and outwardly-projecting lugs D are formed by stamping the metal outwardly.

Outside of the sleeve A, I provide an adjustable sleeve or cylinder C. This sleeve is formed with a spiral groove or thread G, adapted to engage the lugs D, so that the cylinder C may be screwed up and down on

the sleeve A. A lug H limits the downward movement of the cylinder C. When the cylinder C is screwed or forced outwardly, it forces the jaws F into the erasive material E and securely retains the same in position. It is apparent that by adjusting the outer sleeve the erasive material can be quickly and easily adjusted in any position desired.

There are numerous ways of forming the jaws F; but the form illustrated is preferred by me, as it does not abrade the surface of the erasive material.

Spiral threads might be provided as a substitute for the lugs D. The form illustrated, however, is preferred on account of its economy of manufacture.

Other variations will be readily apparent to those skilled in the art to which my invention appertains.

Having thus described my invention, what I claim as new, and desire to secure by Letters Patent, is—

1. In a pencil-tip, the combination of a sleeve A, slotted at one end as at I to receive the end of a lead-pencil, and at the other end, as at B, to receive an elongated piece of erasive material; inwardly-projecting jaws F formed on said sleeve adapted to engage said erasive material; outwardly-projecting lugs D formed in said sleeve; and an adjustable external cylinder C having a spiral groove G adapted to engage said lugs D, whereby the same may be adjusted back and forth on said sleeve, for the purpose specified.

2. In a pencil-tip, the combination of a sleeve A, slotted at one end to receive the end of a lead-pencil and at the other to receive an elongated piece of erasive material; jaws formed on said sleeve adapted to engage said erasive material; suitable guides on said sleeve A; and an adjustable external cylinder C having threads adapted to engage said guides, whereby it may be adjusted back and forth thereon, for the purpose specified.

In witness whereof I have hereunto set my hand and seal in the presence of two witnesses.

WILLARD H. BROWNELL. [L. S.]
